MARSHALL W. HANKS, OF PITTSBURG, PENNSYLVANIA, ASSIGNOR TO
GEORGE WESTINGHOUSE, OF PITTSBURG, PENNSYLVANIA.

METHOD OF MAKING ELECTRIC-LAMP GLOWERS.

SPECIFICATION forming part of Letters Patent No. 735,760, dated August 11, 1903.

Application filed May 18, 1901. Serial No. 60,910. (No model.)

To all whom it may concern:

Be it known that I, MARSHALL W. HANKS, a citizen of the United States, residing at Pittsburgh, in the county of Allegheny and State of Pennsylvania, have invented a new and useful Improvement in Methods of Making Electric-Lamp Glowlers, of which the following is a specification.

My invention relates to methods of making glowlers for electric lamps of the type in which the glowlers are non-conductors when cold and become conductors when heated to a comparatively high temperature.

The object of my invention is to provide an improvement in the art which will cheapen the cost of production of glowlers and render it feasible to easily and expeditiously make any number of glowlers of any given length in order to adapt them to a given voltage.

It has been the usual practice in the manufacture of glowlers to form a rod or string of suitable length and of the desired diameter, then cut such rod or string into suitable sections or lengths, then fuse each end of each of the blanks by means of an electric arc to form a bead, and finally attach terminal wires to the beads by embedding the ends of the wires in the beads or otherwise. It is of course essential that all glowlers intended for use in connection with a given voltage should be of substantially the same diameter and the same length. It has been the practice, therefore, after having formed a bead upon one end of the glower to hold the other end in the arc by means of suitable tweezers and to remove the glower from the arc for the purpose of measuring it. It will be readily understood that several removals of the glower from the arc may occur before the desired length has been reached.

In order to avoid the loss of time incident to the operation above specified and at the same time to insure an exact uniformity in the length of the glowlers, I have devised a method which will now be described, reference being had to the accompanying drawing, in which are shown in side elevation devices which are suitable for practicing my invention.

In the drawing, 1 and 2 are carbon rods or pencils which are included in an electric cir-

cuit and between the adjacent ends of which is formed the arc which is utilized in my process. The outer ends of the carbon rods 1 and 2 are seated in socket-pieces 3, that are rotatably mounted in heads 4, having gear-wheels 5, 6, and 7, that receive motion from a rod or shaft 8, on which the gear-wheel 5 has a sliding non-rotatable fit. The rod or shaft 8 is provided at one end with a handle 9, and the hubs of the wheels 6 are mounted upon screw-rods 10, the inner ends of which are supported by stationary heads 11, which also support the inner ends of the carbon rods 1 and 2.

All of the parts thus far described are supported by a frame 12, that is pivoted at 13 to a standard 14, so as to permit the operator to raise and lower the arc by means of the handle 9. The standard 14 is so mounted on a base-plate 15 as to be turned on a vertical axis by means of the handle 9 to effect any desired lateral adjustment of the arc.

Suitably mounted so as to rotate with or upon a shaft 16 is a table 17, having a suitable number of notches or slots 18, the width of each slot being slightly less than the diameter of the bead 19 on the end of a glower 20, so that a glower may be inserted in each slot and be suspended by means of a previously-formed bead on one end from the upper side of the table. The shaft 16 may be inclined to the vertical, as indicated, so that if all of the notches 18 are provided with glowlers those on the side opposite the arc will not engage with the carbon as the table is rotated. A suitable device 16^a may be employed for adjusting the height of the table in accordance with the length of glower that is desired. The table will obviously be located at a definite height for any given length of glower, and so the lower end of the blank will project substantially into the middle of the arc.

At a suitable distance from the arc is located a fixed screen 21, on which is placed a horizontal line 22, and at a suitable point between the screen and the arc is placed a magnifying-lens 23, the lens being placed in such position as to project upon the screen a magnified image of the arc and the lower end of the glower. Since the employment of a sin-

gle lens will serve to project a reversed image upon the screen, the line 22 will be located at the height corresponding to the length of glower desired. Since the projected image is several times the size of the object, the length may be very accurately measured.

In the use of my method glower-blanks, which have been formed in the usual manner, each with a bead at one end, are placed in the slots 18 in the wheel 17, so that the previously-formed beads rest upon the upper edges of the slots. The frame 12 will then be so adjusted, both vertically and horizontally, as to properly locate the arc with reference to the lower end of the glower-blank at the inner side of the table. Any desired adjustment of the carbon rods with reference to each other may also be effected by rotating the handle 9. It will be seen, therefore, that the operator has complete control of the position of the arc. Inasmuch as the gage-line 22 and the table-slot 18, which is located above the arc, have a definite fixed relation to each other as regards elevation, a given length of glower may always be secured by giving the table a small rotative movement as soon as the inner side of the bead coincides with the gage-line. The glowers may be thus successively moved into position for treatment and as the table is rotated the completed glowers may be removed and their places filled by blanks, thus making the operation substantially continuous.

35 While I have illustrated and described my invention as utilized in connection with the treatment of only the lower ends of glowers, I desire it to be understood that I do not thereby exclude from its scope the treatment 40 of both ends of glowers, either simultaneously or successively.

My invention is obviously not limited to the use of specific apparatus, since any means whereby the blowers may be brought into and held in a definite position in the arc and an enlarged image of the same projected upon a screen having a gage-line will be suitable for practicing the invention.

I claim as my invention—

50 1. The improvement in the art of making electric-lamp glowers which consists in subjecting one end of a glower to the action of an electric arc, simultaneously projecting a magnified image of said glower end upon a gage-screen, and removing the glower from the arc when the image indicates completion of the treatment.

2. The improvement in the art of making electric-lamp glowers which consists in fusing 60 a glower end to form a bead, simultaneously projecting a magnified image of said glower end upon a surface having a gage-line, and

removing the glower from the arc when the image shows completion of the treatment.

3. The improvement in the art of making 65 electric-lamp glowers which consists in supporting a glower in a certain definite position with one end in an electric arc, simultaneously projecting a magnified image of said glower end upon a surface having a gage-line and removing the glower from the arc when the image indicates completion of the treatment.

4. The improvement in the art of making 75 electric-lamp glowers which consists in suspending a partially-formed glower in a certain definite position with reference to a distant gage, simultaneously subjecting the free end of the glower to an electric arc and projecting a magnified image of said glower end upon the gage, and removing the glower from the arc when the image indicates completion of the treatment.

5. The improvement in the art of making 85 electric-lamp glowers which consists in subjecting the lower end of a glower, that is suspended from its upper end, to an electric arc, simultaneously projecting a magnified image of said lower end upon a surface having a gage-line and removing the glower from the 90 arc when the image indicates completion of the treatment.

6. The improvement in the art of making 95 electric-lamp glowers which consists in subjecting a glower to the action of an electric arc to vary its length, simultaneously projecting a magnified image of the arc and glower upon a surface having a gage-line and removing the glower from the arc when the image indicates that the desired length has been 100 attained.

7. The improvement in the art of making 105 electric-lamp glowers which consists in subjecting a glower to an adjustable electric arc to vary its length, simultaneously projecting a magnified image of the arc and glower upon a surface having a gage-line and removing the glower from the arc when the image indicates that the glower is of the desired length.

8. The improvement in the art of making 110 electric-lamp glowers which consists in supporting a glower in a definite position with reference to a gage, subjecting one end of the glower to the action of a movable electric arc, simultaneously projecting a magnified image 115 of said glower end upon said gage, and removing the glower from the arc when the image indicates that the treatment is completed.

In testimony whereof I have hereunto subscribed my name this 15th day of May, 1901.

MARSHALL W. HANKS.
